[57] **CLAIM**

The ornamental design for an interactive telephone station, as shown and described.

DESCRIPTION

FIG. 1 is a front and side perspective view of the present invention.

FIG. 2 is a front elevational view thereof.

The phantom lines in FIGS. 1 and 2 do not constitute a part of the claimed design.

FIG. 3 is a left elevational view thereof.

FIG. 4 is a right elevational view thereof.

FIG. 5 is a bottom view thereof; and,

FIG. 6 is a rear view thereof.

1 Claim, 6 Drawing Sheets

FIG. 3

FIG. 4

FIG. 5

FIG. 6
